AEROSOL SPRAYER

William C. Harris, Racine, Wis., assignor to
S. C. Johnson & Son, Inc.

Application April 26, 1955, Serial No. 35,684

Term of patent 14 years

(Cl. D62—2)

Fig. 2.

Fig. 3.

Fig. 4.

Fig. 1.

Fig. 5.

Figure 1 is a perspective view of an aerosol sprayer embodying my new design.

Figure 2 is a top view of the aerosol spray cap shown in Figure 1.

Figure 3 is a front view of the aerosol spray cap shown in Figure 1.

Figure 4 is a side view of the aerosol spray cap shown in Figure 1.

Figure 5 is a back view of the aerosol spray cap shown in Figure 1.

The dominant features of my design reside in the portions shown in full lines.

I claim:

The ornamental design for an aerosol sprayer, substantially as shown and described.
